CLAIM

The ornamental design for footwear upper, as shown and described.

DESCRIPTION

FIG. 1 is a perspective view of the footwear upper embodying the new design;

FIG. 2 is a top view thereof;

FIG. 3 is a right side view thereof;

FIG. 4 is a left side view thereof;

FIG. 5 is a front view thereof; and,

FIG. 6 is a rear view thereof.

The evenly spaced broken lines represent stitching. The dot-dot-dash broken lines immediately adjacent the solid line portions represent the bounds of the claimed design. All other features of the article shown in dot-dot-dash broken lines are directed to environment and are for illustrative purposes only and form no part of the claimed design.
